UNITED STATES PATENT OFFICE.

JAMES W. SAYRE, OF NEWPORT, KENTUCKY, ASSIGNOR OF ONE-THIRD TO GEORGE VEITH, OF NEWPORT, KENTUCKY.

AUTOMATIC TRAIN-STOPPING DEVICE.

1,295,071.

Specification of Letters Patent.

Patented Feb. 18, 1919.

Application filed January 4, 1916, Serial No. 70,158. Renewed December 30, 1918. Serial No. 269,026.

To all whom it may concern:

Be it known that I, JAMES W. SAYRE, a citizen of the United States, residing at Newport, in the county of Campbell and 5 State of Kentucky, have invented certain new and useful Improvements in Automatic Train-Stopping Devices; and I do hereby declare the following to be a full, clear, and exact description of the invention, such as 10 will enable others skilled in the art to which it appertains to make and use the same.

This invention relates to new and useful improvements in train stopping devices, and has for its principal object to provide a 15 device which may be attached to a railroad train of the ordinary type and which will effectively stop the train should a switch be left open or the semaphore indicate danger.

Another object of the invention is to provide a novel track trip mechanism by means 20 of which a contact may be formed so that current will be completed through the cab of the locomotive and thereby operate an air valve, thus applying the brakes.

25 With these and other objects in view, the invention consists in the novel combination and arrangement of parts which will be fully set forth in the following specification and accompanying drawings, in which,

30 Figure 1 is a diagrammatic view of a train stop constructed in accordance with this invention,

Fig. 2 is an enlarged vertical sectional view of the mechanism carried by the track 35 for completing the circuit, and

Fig. 3 is a horizontal sectional view thereof.

Referring now to the drawings by characters of reference, the numeral 1 designates 40 as an entirety a railroad track comprising the usual rails 2 and 3, while the numeral 4 designates generally a spur or switch comprising the rails 5 and 6, which coöperate with the rails 2 and 3. The switch points 45 which are designated by the numerals 7 and 8 are connected to each other by means of the bar 9, which is provided with a projection 10 which in turn is pivotally connected as at 11 to the lever 12, the lower end 50 of which is pivoted as at 13 to one of the ties. It will thus be seen that when the lever is thrown to either position the switch board will be thrown, thereby providing a mechanical means for controlling the operation of the switch.

The usual semaphore, designated by the numeral 14 is provided and said semaphore comprises the upstanding member 15 having pivotally secured to its upper end the arm 16. This arm carries at one end the enlarged portion 17 to which the flexible member 18 is connected. The opposite terminal of the flexible member is connected as at 19 to the lever 20, which in turn is pivotally mounted as at 21 to any suitable support 60 and the opposite terminal of the lever has pivoted thereto as at 22 the bar 23 which is 65 slideable transversely of the track as clearly shown in Fig. 1. This bar 23 is provided with a suitable contact plate 24 at one terminal, which is arranged to operate within the circuit-closer housing as illustrated in 70 Figs. 2 and 3.

A suitable arm 25 is secured to the connecting bar 9 and a brace rod 26 is arranged 75 to hold the arm 25 rigidly to prevent the same from moving from the angle of 90° with relation to the rod 9. This arm 25 is provided at its end with the angular extension 27, the free end of which terminates in 80 the contact plate 28 which is also arranged to slide in the housing of the circuit-closing element illustrated in Fig. 3.

Carried by the locomotive is a suitable solenoid 29 which is arranged so that when it is energized, a valve will be operated, thereby applying the brakes to the train and causing the same to come to a stop. This solenoid is connected by means of the wire 30 to the brush 31 which is arranged to 90 contact with the wheel 32 carried by the pony truck which wheel is insulated from the wheel 33 and from the remaining portion of the locomotive, thereby forming an electrical connection between the rail 3 and the solenoid 29. The opposite terminal of the solenoid is connected through the wire 34 to a ground circuit which terminates in the frame of the locomotive and is arranged to contact by means of the rail 2 to the 95 ground. A suitable source of power supply 35 is provided and one terminal of the supply has secured thereto the wire 36 which terminates in the contact member 37. This contact member is supported within the housing provided therefor and is arranged to coöperate with the contact member 38 which is also supported in the housing and is connected by means of the wire 39 to the rail 3. These contact 100 members 37 and 38 are connected in series with the solenoid 29. The other terminal of the supply 35 is connected to the rail 3. The 105

2

plates 37 and 38 are arranged to be bridged by means of the plates 24 and 28 of the semaphore and switch respectively, and it will be clearly seen that when the switch is thrown to an open position or the semaphore arm set at danger, a contact will be formed through the plates 37 and 38 thereby permitting the circuit to be closed when the pony truck of the locomotive bridges the remaining gap in the circuit.

10 In order to provide a proper protection for the contact elements there is provided a suitable housing designated generally by the numeral 40. This housing comprises the bottom wall 41, end walls 42, and side walls 43. Each of the end walls is provided with an opening 44 having a collar 45 formed integral therewith, to act as a guide for the rods 28 and 27. A plurality of apertures 46 are also formed in one of the end walls and these apertures are arranged to receive the contact wires 36 and 39, which are connected to the plates 37 and 38 as illustrated in the drawings. A suitable cover 47 is provided for the casing 4 and it will thus be seen that the contact plates will at all times be protected from the elements and any danger of short-circuiting the device is eliminated.

15 20 25 30 35 40 45 50 55 60 65 70 75 80 85 90 95 100 105

While in the foregoing there has been shown and described the preferred embodiment of this invention, it is to be understood that such changes may be made in the combination and arrangement of parts as will fall within the spirit and scope of the invention as defined in the appended claims.

What is claimed is:

1. An automatic train stop including the combination with a locomotive provided with an electrical control for operating the engineer's air valve to set the brakes, of a railroad track, one of the rails of said track being insulated to provide a conductor for an electrical circuit, a circuit closed casing mounted between the rails, contact plates within the casing, said contact plates being connected with a source of current supply and to the insulated rail respectively, the opposite terminal of the source of electrical supply being connected with the other rail, a train carried partial circuit having terminals connected with the rails including train stopping means, a switch for the track, an operating bar connecting the switch points, 55 a contact member carried by the operating

bar and arranged to operate within the casing to close the circuit between the contact plates, and thereby automatically stop the train in case the switch is open.

2. The combination with a locomotive provided with an electrical air valve operating mechanism, of a track, one of the rails of the track being insulated from the other, a circuit closer including a casing, contact plates within the casing, a source of power supply having one pole connected with the other rail, the other pole of the power supply being connected to one of the contact plates, the opposite contact plate being connected to the insulated rail to form a metallic partial circuit, a train-carried partial circuit having terminals connected with the rails including train-stopping means, a slideable bar, a contact plate carried by the bar and arranged to bridge the space between the contact plates and means to actuate the bar.

3. The combination with a locomotive provided with an electrically operated controlling means for the air brake system, of a track, one of the rails of the track being insulated from the remaining portion of the track, a circuit closer provided with contact plates, a slideable bar, means carried by the bar to bridge the contact plates and close the circuit therethrough, an electric circuit including the track rails, locomotive and circuit closer and adapted to be closed by the latter to operate the brake controlling means, and means to actuate the rod.

4. In combination, a locomotive provided with an electrically operated controlling means for the air brake system, a track, one of the rails of the track being insulated from the remaining portion of the track, a circuit closer, a switch in the track, said circuit closer including contact plates, a bar connecting the switch points, an electric circuit including the track rails, locomotive and circuit closer and adapted to be closed by the latter to operate the brake controlling means and means carried by the bar to bridge the contact plates and close the circuit therethrough.

In testimony whereof I affix my signature in presence of two witnesses.

JAMES W. SAYRE.
